US00D612549S

(12) **United States Design Patent**
Garcia-Lucio et al.

(10) **Patent No.:** **US D612,549 S**
(45) **Date of Patent:** **** Mar. 23, 2010**

(54) **HUMMINGBIRD FEEDER**

(75) Inventors: **Alfredo Garcia-Lucio**, Denver, CO (US); **Jim B. McKeever**, Denver, CO (US)

(73) Assignee: **Parasol LLC**, Denver, CO (US)

(**) Term: **14 Years**

(21) Appl. No.: **29/343,907**

(22) Filed: **Sep. 21, 2009**

DESCRIPTION

FIG. 1 is a front perspective view of the hummingbird feeder, showing our new design;

FIG. 2 is a right elevation view of the hummingbird feeder illustrated in FIG. 1;

FIG. 3 is a front elevation view of the hummingbird feeder illustrated in FIG. 1;

FIG. 4 is a bottom plan view of the hummingbird feeder illustrated in FIG. 1; and,

FIG. 5 is a top plan view of the hummingbird feeder illustrated in FIG. 1.
